UNITED STATES PATENT OFFICE

WALTER M. CROSS, OF KANSAS CITY, MISSOURI, ASSIGNOR, BY MESNE ASSIGNMENTS, TO GASOLINE PRODUCTS COMPANY, INC., OF WILMINGTON, DELAWARE, A CORPORATION OF DELAWARE

PROCESS AND APPARATUS FOR CONVERTING HYDROCARBONS

Application filed February 1, 1926. Serial No. 85,157.

This invention relates to improvements in a process and apparatus for converting hydrocarbons, and refers more particularly to a process or method of employing a forced draft or mechanically forced stream of a fluid medium, such as air, through the refluxing stage to assist in the dephlegmation and utilizing the air preheated during this dephlegmation of the hydrocarbon fractions for the entering air to the furnace. Furthermore, novelty lies in the particular type of heat exchanger which is used as the element of heat exchange between the air stream and the vapors rising through the dephlegmating stage or column.

Fig. 1 is a diagrammatic side elevational view of an apparatus in which the method and device may be economically utilized, but it should be understood that the scope of the invention is not to be limited to the particular embodiment shown as it can be as well applied to any type of apparatus in which it is desirable to separate or knock back the higher boiling point fractions and at the same time procure a preheated entering air for the heater or furnace.

Fig. 2 is a sectional detail of the heat exchanger.

In the drawings is shown the invention in connection with the cross cracking process, the details of which have been simplified as the operation is well known in the art and forms no part of the present invention other than to disclose an apparatus upon which the invention may be used.

Referring to the drawings, at 1 is shown a furnace consisting of a fire chamber 2 and a tube chamber 3 in the latter being mounted the heating tubes 4; 5 is a chimney or stack; 6 is a reaction chamber connected to the discharge from the heating tubes by the transfer line 7. The reaction chamber is preferably fabricated from a single ingot by forging, having flanged bottle-neck ends closed by means of removable plates which facilitate the cleaning thereof. It is also heavily insulated to prevent loss of heat by radiation. The evaporator 8 is connected to the discharge from the reaction chamber through a transfer line 9 in which is interposed a pres-

sure reduction valve 10. At 11 is shown a dephlegmator or refluxing tower preferably of the bubble type connected with the evaporator 8 by means of a vapor line 12. An overhead vapor line from the tower 11, designated 13, communicates with the condenser coil 14 positioned in the condenser box 15. The discharge end of the condenser coil 14 terminates in a pipe 16 which communicates with the gas separator 17, the latter being equipped with a liquid draw off line 18 controlled by a valve 19 and a gas draw off line 20 controlled by a valve 21.

In operation, charging stock, supplied to the stock tank 22 from any convenient source through the line 23, is directed through the line 24 and charged, by means of pumps 25 and 26, to the coils 4 where it is raised to a cracking or conversion temperature. The velocity of the oil through the coils and the heating being so regulated that a minimum amount of carbon or polymerized products are separated out due to the heating. The oil is sufficiently heated in the coil so that upon its discharge through the line 7 it accumulates in the reaction chamber 6 to substantially consummate the conversion which was initiated in the coil. This conversion is due primarily to the time period that the oil is maintained in the reaction chamber and the temperature and pressure conditions which it undergoes. In practice, the temperatures and pressures are regulated to prevent substantial vaporization.

On discharge from the reaction chamber, the high pressure is released and the lighter fractions are permitted to evaporate from the oil body in the evaporating tower 8. Steam or a cooler hydrocarbon may be introduced through the pipe 27 controlled by a valve 28 to regulate the degree of evaporation and the character of bottom which is drawn off from the tower through the line 29 controlled by a valve 30, the latter valve being manipulated either manually or mechanically by a liquid level regulating device not shown. The products withdrawn from the evaporator are directed to a cooler 31 and thence to storage through the pipe 32. The overhead material passing through the vapor line 12 is in-

troduced into the bottom of the refluxing tower and rises in an opposed direction to a gravitating liquid condensate which is constantly being separated from the vapors in the column. This condensate collecting in

5 the column. This condensate collecting in the bottom of the tower is drawn off through the pipe 33 and may be directed immediately to the charging pipe 24 or diverted through the line 34 to the tank 22 by manipulation of the valves 35 and 36.

10 The control of the outlet temperature of the vaporous fractions from the tower 11 by means of a relatively cooler air stream is accomplished by means of a heat exchanger 37 which is positioned at or in the top of the

15 which is positioned at or in the top of the tower 11. This heat exchanger preferably comprises a plurality of sets of corrugated sheets arranged in the manner described in my previous applications Serial No. 35,571,

20 dated June 8, 1925, and Serial No. 79,772, dated January 7, 1926. Two corrugated sheets are combined to form a set designated as 38 in Fig. 2. These sets are arranged in the manner shown in Fig. 2 and the vapors

25 permitted to rise vertically through the sinuous or tortuous ducts 39. The air, on the other hand, is forced to follow the

the other hand, is introduced from the atmosphere through the duct 40 and circulated by means of a blower fan 41 driven by a motor 30 42 and directed to the header 43 communicating with the straight tube-like ducts 44. In the drawings, the stream of air is shown as passing but once through the tower but it should be understood that the stream may be

35 should be understood that the stream may be reversed as many times as it is found necessary to procure the desired amount of cooling and greatest efficiency of heat exchange. This may be accomplished by providing conduit 51 provided with valve 52 by means of

40 which air, after passing through the heat exchanger, may be returned to the low pressure side of the blower. The air utilized in this

45 manner as a refluxing medium is preheated and is discharged from the exchanger through the duct 44a and introduced to the

fire chamber 2 of the furnace 1. This pre-heated air considerably increases the efficiency of the furnace as it requires considerably less heat to bring up the temperature

if the air introduced to the fire chamber is at a relatively high temperature. This practice of utilizing an air stream as a refluxing me-

55 dium and employing the preheated air as the entering air to the furnace, may be supplemented, if desired, by recycling a portion of the hot stack or flue gases if these gases are

above the temperature of the preheated air; if, however, they are below this temperature, 60 their recycling would not improve the efficiency as they would tend to lower the temperature of the air entering the furnace.

It is of importance in the conversion of hydrocarbon oils to control within a relative-
ly limited range the character of the mate-
rials entering the furnace.

rial which passes overhead from the refluxing tower. This may be done by controlling the heat exchange, which factor is dependent primarily upon the volume of air which is passed through the exchanger and which is brought in exchange relationship with the vapors. In order to automatically obtain this control, a thermocouple or pyrometer 45 is positioned in the top of the tower which has electrical connections 46 with a relay switch 47, the latter regulating the speed of the motor 42 which drives the fan 41, resulting in the varying in the volume of air which is introduced and circulated through the heat exchanger. 70 75 80

A discharge pipe 48 and dampers 49 and 50 serve to control the amount of air which is introduced to the furnace and maintain a relatively constant supply. Such control may be necessitated by a variance or change in the volume of air produced by the relatively different amounts of air supplied to the tower through the automatic control of the blower fan. 85

I claim as my invention:

1. A process for converting petroleum hydrocarbons comprising heating oil to cracking conditions of temperature and pressure in a heating stage, passing the heated oil to conversion, evaporating and dephlegmating stages and controlling the character of the vapors discharged from the dephlegmating stage by submitting the vapors to heat exchange relationship with a mechanically driven cool air draft regulated to effect said control; passing air preheated by the discharged vapors to the heating stage, and returning a portion of the preheated air to the cooler air draft, whereby the said air draft is maintained at a predetermined temperature.

2. In an apparatus of the character described comprising heating and dephlegmating devices, in combination, mechanically driven cool air draft means and an associated heat exchanger positioned on the dephlegmator, an air duct leading from the heat exchanger to the heater and adapted to deliver heated air thereto, and means for recycling the heated air. 110

3. An apparatus for treating oil comprising a furnace, a heating element in the furnace through which oil to be treated is passed, a vaporizer adapted to receive the heated oil, a dephlegmating tower, means for conveying vapors from the vaporizer to the dephlegmating tower, said tower having a vapor discharge outlet, a heat exchanger associated with said outlet for cooling vapors passing from the tower, means for forcing air through said heat exchanger in heat exchange relation with the vapors, a conduit connecting the air discharge portion of said heat exchanger with the furnace for supplying preheated air to the latter, and means

connecting said conduit with the low pressure side of the air forcing means for recycling a portion of the air discharged from the heat exchanger.

- 5 4. In an oil treating apparatus, a dephlegmating tower, means in said tower for dephlegmating vapors passing therethrough, means for introducing vapors into the tower, said tower having a vapor discharge outlet,
- 10 a heat exchanger associated therewith for cooling vapors passing from the tower, a blower associated with the heat exchanger for forcing a current of air therethrough in heat exchange relation with said vapors, said
- 15 heat exchanger having a discharge outlet for air passing therethrough, and a conduit associated with the air discharge outlet and connected with a low pressure portion of said blower for recirculating a portion of the dis-
- 20 charged air through the heat exchanger.
